RADIO BEACON WITH QUADRANT IDENTIFICATION

Andrew Alford, New York, N. Y., assignor to
Federal Telephone and Radio Corporation, a
corporation of Delaware

Application December 17, 1941, Serial No. 423,252

7 Claims. (Cl. 250—11)

This invention relates to radio range beacons and more particularly to two-course radio range beacons provided with quadrant identification means.

Radio beacons providing sharply directed two-course guide lines have been proposed in the past. One difficulty encountered when using these beacons particularly for radio range purposes is that an aircraft coming within the field of the beacon cannot be sure of his location with respect to the beacon location. In other words, he can tell when he is on one side or the other of the range defined by the beacon but cannot ascertain which direction along the range corresponds to his position. This difficulty can be overcome if some means is provided for identifying the quadrants so that the pilot will know his position with respect thereto.

According to my invention I provide a novel arrangement for producing identification signals which will overcome the difficulties encountered in ordinary two-course radio range beacons.

In accordance with one of the principal features of my invention I provide quadrant identifications in the form of a second radio beacon arrangement adjusted to define a line at right angles to that defined by the main beacon. This second radio beacon is keyed or otherwise provided with identifying signals to distinguish it from the main beacon and is adjusted preferably to transmit only side band energy to prevent unwanted interaction between the carrier frequencies on the main course.

According to a further feature of my invention I provide means for minimizing interaction between the two radio beacon arrangements to further prevent undesirable interference along the course.

While I have outlined above the general features and objects of my invention a better understanding may be had from the particular description made with reference to the accompanying drawing in which

Fig. 1 is a schematic wiring diagram of a radio beacon made in accordance with my invention, and

Fig. 2 is a diagram of the field patterns for the purpose of explaining the operation of my invention.

Turning to the drawing, reference character 1 designates a radio frequency source from which energy is fed through modulators 10 and 11 and a balancing network 12 to the three antenna units 2, 3 and 4 of the main two-course radio beacon. This radio beacon is of the type gen-

erally similar to one previously proposed. It should be distinctly understood, however, that this illustration is made merely as an example and other known types of radio beacons may be used. Radio frequency energy modulated at two frequencies F1, F2, which may for example, be 90 and 150 cycle notes are fed directly to central radiator 3 over line 17, with the carriers in phase and from this central radiator the carrier frequency as well as the modulation side bands are radiated. The energy fed to radiators 2 and 4 contains no carrier frequency but substantially only the modulation side bands provided by modulators 10 and 11. The feed line between radiators 2 and 4 is provided with a transposition so that these units which as shown are loops for radiation of horizontally polarized energy, are fed in phase opposition.

Loops 2 and 4 are preferably spaced a distance 20 in the order of 165 electrical degrees from central radiator 3. The central radiator 3 in this instance should preferably have no parasitic effect on side radiators 2 and 4, since it must also supply carrier for the quadrant identification 25 beacon to be later described. This effect may be accomplished by making line 12 which interconnects these two radiators electrically equal to an integral multiple of half-wave lengths. By making the line of such a length, the center point 30 at which feeding occurs is effectively a short circuit. Accordingly, the junction point of line 12 with each of the feed lines to antennae 2 and 4 then looks like an open circuit so far as radiators 2 and 4 are concerned and no parasitic effect is 35 produced in the side radiators. While this point may be ascertained by calculation, it has generally been found that the precise connection point may be more readily determined experimentally. Antenna 2, for example, is disconnected from all 40 the feed lines and energy is supplied only to central radiator 3. A short circuiting bar is then placed across line 12 and its position adjusted until meter readings show no energy in loop 2. A similar procedure is then effected for radiator 45 4. The two points found by the short circuiting bar are then joined and line 17 is coupled at this junction point.

The beacon arrangement of radiators 2, 3 and 4, then produces substantially the pattern 200 shown in solid lines in Fig. 2 neglecting minor lobes. This is the normal two-course beacon pattern and has the drawbacks outlined above.

In order to produce the quadrant identification I provide a second beacon arrangement consisting of antenna units 2A, 3A and 4A, arranged

at right angles to beacons 2, 3 and 4, and preferably at a different level therefrom so that loops 3 and 3A, are vertically spaced one above the other. Energy from source 1 is fed to balanced modulator 14 in which it is modulated by tone energy from source 15, for example, at a thousand cycle note. The output from the modulator 14 therefore consists of side band energy only.

The side band energy from 14 is fed over line 17A directly to central loop 3A and is fed through a keying switch 16 and line 12A to the two side radiators 2A and 4A. Switch 16 is preferably arranged to produce interlocking keying signals such as A and N. However, if desired, any different keying signals may be produced so long as proper identification may be produced thereby. The tie line 12A interconnecting radiators 2A and 4A, is preferably made to have the same characteristic as tie line 12, that is so as to produce no parasitic action in radiators 2A and 4A.

The radiators 2A and 4A are preferably spaced closer to one another than are radiators 2 and 4. The reason for this closer spacing is that the field produced by the auxiliary identification beacon is at right angles to the normal course line. As a consequence the minor lobes are of greater importance and a narrow spacing is provided to reduce the amplitude of any such minor lobes. The spacing of antennae 2A and 4A from central antenna 3 is preferably made between 90 and 120 electrical degrees.

With this second beacon arrangement a pattern such as shown in dash lines at 201 of Fig. 2 is produced. It can, therefore, be seen that in quadrant NW the 90 cycle and A signal predominate, in quadrant SW the 150 cycle and A signal predominate, in quadrant SE the 150 cycle and N signal predominate and in quadrant NE the 90 cycle and N signal predominate. As a consequence the pilot flying into the range of the beacon will be immediately apprised of his position with respect to the beacon itself and the 180 degree ambiguity is fully overcome.

While the beacon described above is useful without any further changes it can be realized that some reaction between loops 3 and 3A will occur. As a consequence some of the energy from loop 3 may be fed directly to loop 3A and vice versa. This leads to some confusion due to overlapping of the signal patterns. The difficulty may be overcome by feeding some of the energy supplied to loop 3 to loop 3A and vice versa in an amount just sufficient to compensate for the interaction. To accomplish this a line 18 is coupled to an intermediate point of feed line 17 and to an intermediate point of feed line 17A supplying energy to antennae 3 and 3A, respectively. Line 18 may be provided with a phase shifter 19 if desired and the position of the connection point of line 18 and line 17A, as well as adjustment of the phase shifter is made until there is no effective reaction remaining between loops 3 and 3A. With this adjustment then the effective broadening of the courses by interaction is completely overcome and patterns 200 and 201 of Fig. 2 are clearly defined.

While I have described above a particular embodiment of my invention in connection with the preferred inserted diagram, it should be understood that this description is made by way of illustration. It should also be distinctly understood that the provisions for preventing interaction between antenna units of an array may be useful in connection with other combinations than that illustrated. Furthermore, the broad

principles of my invention are not limited to beacons of the particular design illustrated but may be applied to other forms thereof. Moreover, antenna units having vertical polarization effects may be used in place of the type illustrated without departure from the spirit or scope of my invention. Many other modifications may be made to my invention within the scope thereof without departing from the spirit of my invention.

What is claimed is:

1. A radio beacon comprising a first plurality of radiators, a source of radio frequency energy, first modulation means for applying distinctive signals to said radio frequency energy, means for applying said distinctively modulated signals to said first plurality of radiators to produce distinctively modulated overlapping fields of radio frequency defining a course line, a second plurality of radiators arranged transversely of said first set of radiators, a tone frequency source, a balanced modulator coupled to said radio frequency source and said tone frequency source to produce side band modulation energy, said keying means for applying said side band modulation energy to said second plurality of radiators in alternately different phase relation to produce effectively overlapping fields of energy transversely of said distinctively modulated fields.
2. A radio beacon comprising a first set of three radiators arranged in a line, a radio frequency source, means for modulating energy from said radio frequency source with two distinctive modulation signals, means for supplying the modulated energy to said radiators in phase relation to produce two effective overlapping fields of energy defining a course line, a second set of three radiators arranged in a line at substantially right angles to said first named line, a source of tone frequency, means for modulating energy from said radio frequency source with said tone frequency to produce substantially only side band energy, means for supplying said side band energy to the center radiator of said second set, and means for applying said side band energy in alternately phase reversed relation to the outer radiators of said second set to produce alternately keyed radiation patterns defining a line substantially at right angles to said course line.
3. A radio beacon according to claim 2, further comprising means interconnecting the outer radiators of said first and second sets respectively, said interconnecting line being so adjusted and arranged that said outer radiators are effectively open circuited with respect to received radiated energy.
4. A radio beacon according to claim 2, further comprising means for feeding energy between the central antennae of said first and second sets, and means for adjusting the phase and amplitude of said fed energy to neutralize parasitic intercoupling of said radiators.
5. A radio beacon according to claim 2, further comprising means interconnecting the outer radiators of said first and second sets respectively, said interconnecting line being such that said outer radiators are effectively open circuited with respect to received radiated energy, and means for feeding energy between the central antennae of said first and second sets, and means for adjusting the phase and amplitude of said energy to neutralize parasitic intercoupling of said radiators.

6. A radio beacon comprising a central radiator, a pair of side radiators spaced on opposite sides of said central radiator, means for supplying energy to said central radiator, and to said side radiators, and means for substantially eliminating parasitic effects of said side radiators from said central radiator comprising a transmission line interconnecting said side radiators, said transmission line being substantially electrically equal to an odd integral multiple of a half wavelength at the operating frequency.

7. Radio beacon system affording quadrantal indications, including a first beacon unit arranged to produce a first set of two overlapping radiation patterns defining a course line, means for supplying continuous audible frequency mod-

ulation signals differing for each of said patterns, a second beacon unit arranged to produce a second set of two other overlapping radiation patterns, said first and said second sets of radiation patterns respectively defining discrete course lines positioned at ninety degrees to one another, and means for producing differing keyed audible modulation signals for each of said patterns of said second set, whereby received signals from said system have two sets of characteristic modulation signals, each set including two differing signals and whereby four permutations of received signals are possible, each permutation defining a predetermined quadrantal position.
